DOOR SPRING AND STOP

Filed Feb. 3, 1928

Fig. 2.

INVENTOR.
Ralph M. La Barr
BY David E. Carlson
ATTORNEY.

UNITED STATES PATENT OFFICE

RALPH M. LA BARR, OF ST. PAUL, MINNESOTA

DOOR SPRING AND STOP

Application filed February 3, 1928. Serial No. 251,528.

My invention relates to a combination door spring and stop device the object of which is to provide an attachment for doors having a spring for resisting the opening movement of a door and normally holding it closed and further means operating in conjunction with said spring to positively prevent a door from being swung open beyond a certain predetermined position. It is obvious that the latter function of my device prevents a door from being swung back accidentally or by a strong wind in which case any glass in the door is easily broken or other damage may occur. A further object is to provide a simple, efficient and inexpensive device for the purpose described and as illustrated in the accompanying drawing, in which,—

Fig. 1 is a top view of my device in operative position connected with an outer door of a building, portions of the wall adjacent the door being shown in section.

Fig. 2 is a vertical elevation about as on line 2—2 in Fig. 1 but showing the upper parts of the door frame more fully.

Figs. 3 and 4 are respectively a face view and an edge view of one of the fixed hook members of my device.

Figs. 5 and 6 are respectively a top and face view of a stop cam used with my door device.

Referring to the drawing by reference numerals 5 designates a wall with a door frame constituting the upright frame members 6 and horizontal top frame piece 7, on the inner faces of which are fixed or formed in the said frame the continuous separators strip 8—8A of which 8 are the vertical and 8A the horizontal upper strip. 9 is the usual inner door hinged as at 10. 11 designates an outer door hinged as at 12 to frame 6 and adapted to be swung outwardly from the wall as indicated by arrow 13 in Fig. 1. Said outer door may be either a screen or storm door or a permanent door. My de-

vice is of course equally applicable to other doors regardless of which direction they swing from a wall as will presently be more fully understood.

14 are two identical brackets used in mounting my device, each comprising preferably an elongated plate with perforations 14P for screws 14S and from one side of said plate projects an integral preferably L-shaped hook 14H. One hook member, as to the right in Figs. 1 and 2 is attached to the horizontal door frame member 8A near the hinged side of the door 11 and the outer is attached to the door in spaced relation horizontally from the first described hook member and having their hooks projecting in opposite directions. 15 is a close-coiled spring with integral ring members 15R, one at each end and adapted to be engaged simultaneously on the shanks of the hook members 14 as shown with the spring tensed somewhat when the door is closed. 16 is a metal bar extended through the spring and having an eye 16H at one end adapted to engage the hook member 14 on the door frame and alongside of the spring hook 15R thereon (see Fig. 2). The opposite end of said bar projects beyond the other end of spring 15 and its free end terminates in a downwardly directed part 16S (see Figs. 2 and 6) hereinafter termed the stop. In opening a door as from full to dotted line positions in Fig. 1 it is obvious that the distance between brackets 14 is increased causing spring 15 to be extended and resist opening movement. Simultaneously the hook or stop end 16S is gradually brought closer to the hook or finger 14H of the door bracket and will engage the latter (as dotted position 13 in Fig. 1) and thus the door is brought to a positive stop. The widest open position of the door can be determined at any time by simply arranging hook 16S where it needs to be to engage the door bracket at that position. For example in

Fig. 1 the door is limited to an open position at approximately right angles to the wall. It is obvious that if the door opening movement is thus positively checked, the door can not slam back against the wall.

I have also provided a stop device comprising an L-shaped finger-operated cam 17 pivotally secured as at 18 to the door 11 just below member 14 (see Fig. 2) one arm of said cam being bent out as 17A and adapted to be swung into the path of stop arm 16S and outwardly thereof on the door (see Figs. 5 and 6). When the rod 16 is thus prevented from sliding it is obvious that the door will be securely held in open position. To release cam 17 it is only necessary to swing it to one side with the obstruction arm 17A out of the path of movement of the rod (see Fig. 2) and the stretched spring 15 will immediately close the door.

It is further obvious that the shank of arm 14H on the fixed bracket 14 secured to the door frame serves as a fulcrum or pivot for the eyelet or loop 16H of bar 16 and the ring 15R of the spring.

The use of my device has been fully disclosed in the foregoing specification. It might be added however that in the mounting of my device the rod 16 may need to be sprung at the end protruding from the spring so that its free end will be parallel to the adjacent face of the door and will thus not contact with or mar the door when being drawn toward the spring end.

I claim:

1. In a door closing and stop device of the class described, two counterpart pivot brackets, one adapted to be fixed to the upper horizontal door frame member adjacent the hinged edge of a door, the other adapted to be fixed to the door in spaced relation horizontally from the first bracket, an elongated close coiled tension spring pivotally engaging said brackets with its opposite ends and under tension when the door is closed, a rod extending longitudinally through said spring and one end thereof pivotally engaging the bracket fixed on the door frame and its other end protruding normally beyond the bracket on the door in parallel spaced relation to the said door, and a downwardly directed hook on the latter extremity of the said rod, said hook adapted to engage the bracket on the door when the latter is swung to a predetermined open position, and a stop member pivotally secured on the door outwardly of its spring bracket to engage the said hooked part of the rod and hold the door open, each of said brackets comprising a flat base and an integral L-shaped arm projecting therefrom with one part of said arm at right angles to the plate and the extremity in parallel relation to the base.

2. The structure specified in claim 1 in

which said stop member comprises a bell crank lever pivotally securable to the door near its spring bracket, a projection on one arm of said lever adapted to be swung into contact with the outer part of the said hook on the rod when said hook is in engaging position with the door bracket for the purpose described.

In testimony whereof I affix my signature.

RALPH M. LA BARR.
